BUTTER DISH OR SIMILAR ARTICLE

Martin Schnur, West Orange, and Mel Appel, Murray Hill, N.J., assignors to Deka Plastics, Inc., Elizabeth, N.J.

Filed Oct. 4, 1960, Ser. No. 62,365

Term of patent 3½ years

(Cl. D44—5)

Figure 1 is a side elevational view of a butter dish or similar article, showing our new design;

We claim:

The ornamental design for a butter dish or similar article, as shown.
